By his Attorney,
Nelson W. Howard

UNITED STATES PATENT OFFICE.

WILLIAM C. BAXTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

CUTTING MACHINE.

Application filed May 19, 1921. Serial No. 470,875.

To all whom it may concern:

Be it known that I, WILLIAM C. BAXTER, a citizen of the United States, residing at Beverly, in the county of Essex and State of Massachusetts, have invented certain Improvements in Cutting Machines, of which the following description, in connection with the accompanying drawings, is a specification, like reference characters on the drawings indicating like parts in the several figures.

This invention relates to cutting machines and more particularly to machines for cutting blanks from sheet material.

In the feeding of sheet material to cutting devices feed rolls or cylinders are quite commonly employed because of the simplicity of construction in the feed operating means and the efficiency of the rolls or cylinders both in feeding and guiding the sheet material to cutting position. Since the extent of the surface of the stock which is frictionally engaged by the feed roll or cylinder during feeding operations varies with the size of the feed rolls employed, it is clear that the size of the feed rolls should be carefully determined with relation to the weight and surface characteristics of the stock to be fed. Heretofore in the feeding of relatively heavy stock, where feed rolls have been employed they have been of such a size and so positioned that a considerable space has been left between the feed rolls and the cutter to which the stock is being fed. Even when the rolls were placed as closely adjacent as possible to the cutting means in such prior constructions a space was left in which a substantial end portion of the material remained unfed between the rolls and the cutting means.

It is an object of the invention to provide improved means for feeding the described end portion of the stock into proper cutting position.

In one aspect, the invention resides in an improved feeding means for sheet material wherein feed rolls are provided which are so constructed and arranged as to insure the proper feeding of every portion of each sheet presented thereto so that no substantial portion thereof remains unfed.

From another viewpoint, the invention contemplates the provision of auxiliary feeding means located and operating be-

tween the main sheet feeding means and the cutting means for assisting in the feeding of the sheet material and particularly for progressively engaging different portions of a surface of the end portion of each sheet after it passes from the control of the main sheet feeding means to position it in definite relation to the cutting means.

In the illustrative machine a relatively small feed roll is disposed closely adjacent to the cutting means and is so mounted as to engage the upper surface and also an end surface of the described end portion of the stock to move the latter to proper position with respect to the cutting means. Preferably the auxiliary feed device is so constructed as to engage the upper surface of the material at a plurality of points separated a considerable distance from each other in a direction transverse to the line of feed thereby insuring better control of the material during feeding thereof.

It is a further object of the invention to provide improved means for directing the advance end of the sheet material being fed properly into the field of cutting operations.

Conveniently the feed roll which, in the illustrative construction, serves to feed the end portion of the sheet material to the cutting means operates also to guide the advance end of each sheet into proper relation to the cutting means.

Other important features of the invention, including combinations of parts and details of construction, will be described in the specification and pointed out in the appended claims.

In the drawings:

Figure 1 is a sectional view through the illustrative cutting machine showing the novel feeding means and its relation to the cutting means, the section being in part along the line 1-1 of Fig. 2;

Fig. 2 is a section along the line 2-2 of Fig. 1; and

Fig. 3 is a detail view in perspective of a portion of the feeding means.

In the illustrative embodiment of the invention there is provided a table 4 for supporting the work and guiding it to the first pair of feed rolls 6 which seize the sheet material and feed it onwardly into the grip of a second pair of feed rolls 8, the said feed rolls being mounted in brackets 10 and 12.

in such manner that the feed rolls cooperate with each other on opposite sides of the plane of the sheet material which is being fed. Since the cutting operations are performed through the operation of members which have a relative reciprocatory movement, means (not shown) is provided for intermittently rotating the feed rolls so as to feed the stock step by step into proper cutting position. As shown, the cutting means comprises a die 14 having an upwardly facing cutting edge upon which the sheet material is forced by the cutter plate 16 secured to the block carrier 18 which receives reciprocatory motion through a pitman 20 from a source of power not shown. In order that the incoming sheet of material may be introduced into the grip of the feed rolls 6 at the proper time there is provided a stop plate 22 pivotally supported at 24 by a holder 26 which is slidable vertically within a bearing 28 through connections comprising a rod 30 connected by means of a sleeve 32 to a crank arm 34 secured to the rock shaft 36. When the sheet material is in position beneath the stop 22, downward movement of the crank arm 34 serves merely to compress the spring 38 which surrounds the rod 30. When however the material is passed from below the stop 22 the latter is pressed down upon the table and is interposed in the path of the oncoming sheet and is withdrawn at the proper time to permit of the movement of the sheet into the grip of the feed rollers 6, thus ensuring that the forward end of the sheet will be positioned properly with respect to the die 14 for the first cutting operation. In the illustrative machine a supporting plate 40 is provided pivoted at its rear end at 42 to the table 4 and positioned between sections of the lower feed rolls 6 and 8 so as to furnish an additional guide and support for the sheet material passing through the feeding means, the forward end of the supporting plate resting upon a stripper member 44 carried at the rear end of the arm 46 which is yieldingly held by means not shown with the stripper member in position to support the adjacent end of the plate 40 and the work slightly above the plane of the cutting edge of the die as will be clear from an inspection of Figure 1 of the drawings. Upon descent of the cutter plate and carrier 18 a lug 48 secured to the block carrier and having its lower face in the same plane with the cutting surface of the plate 16 engages with the upper surface of the work to depress the work along with the front end of the supporting plate 40 and the stripper member 44 at the same time that the work is being forced upon the die 14, thus preventing any abrupt folding or bending of the material adjacent the die while a blank is being cut therefrom. As the block carrier 18 rises

the stripper plate 44 moves upwardly to strip the material from the die and to carry it into position in a plane slightly above the cutting edge of the die so that there will be no obstruction to the forward feeding of the material preliminary to a succeeding cutting operation. The operation of the mechanism thus far described will be understood as involving the feeding of sheet material intermittently to the die 14 by means of the feed rolls 6 and 8 after a preliminary positioning of each sheet through the operation of the stop 22. For a more detailed description of the feeding and cutting means described in the foregoing portion of this specification, reference should be had to United States Letters Patent No. 1,344,975, granted June 29, 1920, upon application of William C. Baxter.

It will be observed that the feed rolls 8 are spaced a considerable distance from the adjacent edge of the die 14 and hence additional feeding means must be provided in order to take care of the end portion of the sheet material being fed after it passes beyond the grip of the feed rolls 8. In other words, an end portion of material is normally left in the space between the rolls 8 and the adjacent edge of the die 14 to be fed by some auxiliary feeding means which, in the illustrative construction embodying applicant's invention, comprises a relatively small feed roll 50, or rather two feed rolls 50 located closely adjacent to the near edge of the die 14 and spaced a considerable distance from each other and provided with teeth to engage firmly with the upper surface of the sheet material and feed the same forwardly into position over the die at the same time retaining perfect control of the sheet material being fed. As shown, the feed rolls 50 are integral with or securely attached to gear wheels 52 mounted rotatively upon a shaft 54 carried by the lower end of a bar 56 mounted slidably in a guideway 58. For holding the feed rolls yieldingly in contact with the work and for moving the feed rolls downwardly for a purpose that will be hereinafter described, there is provided a spring 60 located in a socket in the upper end of the bar 56 and pressed upon by an adjustable set screw 62. Conveniently the feed rolls 50 are driven by connections with the upper feed rolls 8, the arrangement being such that the small feed rolls 50 are intermittently operated in synchronism with the large feed rolls and at the same peripheral speed. As shown, the operating connections comprise gear wheels 64 conveniently secured each to a side of an adjacent upper feed roll 8 by a screw 65, and small gear wheels 68 held constantly in mesh with gears 64 and with the small gears 52. For holding the gear wheels 68 each in mesh with its corresponding gear 64 there is pro-

vided a link 70 having two arms 72, one on each side of the bar 56 and having bearings 74 which surround and maintain the shaft 76 at a fixed distance with respect to the center of the shaft 66 whereby the gears 68 carried by the shaft 76 are held constantly in mesh with the gear wheels 64. The gears 68 are in turn held in mesh with the gears 52 and hence the shaft 76 is also mounted in the bar 56 which carries the shaft 54 for the lower pair of gears. Since the bar 56 is movable vertically, the shaft 76 is so mounted within the bar that the said movement may take place without disturbing the relation between the various sets of gears. It is for this reason that the shaft 76 is mounted in a slot 78 in the bar 56, the said slot, however, being so shaped as to maintain the shaft 76 constantly at the same distance from the shaft 54. As shown, the link 70 has flanges 80 (Fig. 3) at opposite side portions which are receivable in circular slots 82 (Fig. 1) in the opposed side faces of the gears 64, the mounting of the link 70 being such as to permit movement of the link and, therefore, of the gears 68 about the center of the shaft 66, while maintaining the said gears constantly in mesh with the large gear wheel 64. Since the feed rolls 50 are mounted in the lower end of the bar 56 which is spring-pressed downwardly, the said feed rolls operate to hold the sheet material properly on the support and guide its forward edge into the space between the cutting plate 16 and the die 14, the rotation of the members 50 being a distinct aid in the guiding function of said members. Another particular advantage of the feed rolls 50 lies in their position closely adjacent to the near edge of the die 14 so that the material is controlled during its movement by means operating close up to the die. Furthermore, by mounting the feed rolls 50 upon the movable bar 56 the rolls are carried downwardly into engagement with the rear edge surface of the piece of material as it passes by, thus enabling the feed rolls to move even nearer to the die and to position the rear edge of the sheet material being fed in close juxtaposition to the near edge of the die. It will thus appear that the feed rolls 50 provide means interposed between the large feed rolls and the die for positively controlling the end portion of the sheet material and feeding it into cutting position and for positioning the said end portion with one of its edges so close to a cutting side edge of the die as to ensure that a perfect blank will be formed, providing the said end portion is large enough to provide a blank when positioned with the greatest care with respect to the die.

Conveniently, the lower end of the bar 56 furnishes a support for the stop plate 22 in conjunction with the holder 26 above de-

scribed. As shown, a link 84 (Figs. 1 and 3) pivotally connects the rear end of the stop plate with the lower end of the bar 56, the link 84 being received in a recess in the lower end of the bar. It will be understood that after the material passes beyond the feed rolls 8, the plate whose forward end constitutes the stop 22, will be carried downwardly with the holder 26 to position the stop 22 in proper position to engage the forward end of a fresh sheet of material being introduced into the machine. After the material passes the stop 22 at the forward end of the stop plate it is fed forwardly by the rolls 6 and 8, as described, and finally lifts the feed roll 50 and is engaged thereby to be directed into the cutting means in proper position with respect to the die 14 and hence it will be seen that the feed rolls 50 may perform an important office in addition to that of feeding the end portion of the sheet material as set forth in detail in the foregoing description.

Having thus described the invention, what is claimed as new and desired to be secured by Letters Patent of the United States is:—

1. In a machine of the class described, cutting means, means for feeding sheet material to the cutting means, the construction and arrangement being such that the feeding means is spaced from the cutting means, and means for feeding the end portion of the sheet material after it leaves the first mentioned feeding means constructed to control positively the movement of said end portion to cutting position.

2. In a machine of the class described, cutting means, means spaced from the cutting means for feeding sheet material thereto, and means interposed between the cutting means and the first-mentioned feeding means for feeding the end portion of the material a predetermined distance to the cutting means.

3. In a machine of the class described, cutting means, means spaced from the cutting means for feeding sheet material thereto, and positively operated means constructed to engage and control the end portion of the material for feeding the same into definite relation with respect to the cutting means.

4. In a machine of the class described, cutting means for sheet material, feed rolls, for feeding sheet material to the cutting means, constructed to engage both the upper and lower surfaces of the sheet material, the construction and arrangement being such that the feed rolls are spaced from the cutting means, and means interposed between the feed rolls and the cutting means for engaging the end portion of the material after it leaves the feed rolls to feed the same into definite relation with respect to the cutting means.

5. In a machine of the class described, cutting means for sheet material, feed rolls, for feeding sheet material to the cutting means, constructed to engage both the upper 5 and lower surfaces of the sheet material, the construction and arrangement being such that the feed rolls are spaced from the cutting means, and means engaging the upper surface of the sheet material to feed the end 10 portion thereof located between the feed rolls and the cutting means into proper position with respect to the cutting means.
6. In a machine of the class described, cutting means for sheet material, feed rolls 15 spaced from the cutting means and operative to feed the sheet material to the cutting means, means for driving the feed rolls comprising a gear wheel, and means driven from said gear wheel for engaging the portion 20 of the sheet material between the feed rolls and the cutting means for feeding the same into proper position with respect to the cutting means.
7. In a machine of the class described, a 25 cutter, a table for supporting sheet material, feed rolls for feeding the sheet material toward the cutter, and a presser foot for holding the sheet material upon the table at a point closely adjacent the cutter during 30 a cutting operation, said presser foot comprising a feed roll operative to direct the advance end portion of the sheet material into cutting position.
8. In a machine of the class described, a 35 cutter, a support for sheet material, a feed roll spaced from the cutter for feeding the sheet material thereto, and a relatively small feed roll interposed between the first mentioned feed roll and the cutter and operative 40 at the same speed as the first-mentioned roll for engaging the portion of the sheet material between the first mentioned feed roll and the cutter for feeding the same into cutting position.
- 45 9. In a machine of the class described, a cutter, a support for sheet material, a cutter block for forcing the sheet material upon the cutter, the support being constructed to move with the cutter block, a feed roll spaced 50 from the cutter to feed the sheet material thereto, and means interposed between the feed roll and the cutter and arranged to move with the support and operative to feed the end portion of the material located 55 between the feed roll and the cutter into cutting position.
10. In a machine of the character described, a cutter and a cutting block relatively reciprocable to effect cutting operations upon sheet material, a support for sheet material, a feed roll spaced from the cutter for feeding sheet material thereto, and means interposed between the feed roll and the cutter for engaging the upper surface 60 of the material and an end surface thereof to feed said end portion after it leaves the feed roll into definite cutting position with respect to the cutter.
11. In a machine of the character described, 70 a cutter, and a cutter block relatively reciprocable toward and from each other in cutting operations, a support for sheet material, feed rolls spaced from the cutter for feeding sheet material thereto, a gear wheel connected to one of said feed rolls, a relatively small feed roll mounted closely adjacent to the cutter for feeding the sheet material after it has passed beyond the first mentioned feed roll, and means driven from the gear wheel for operating the small feed roll.
12. In a machine of the character described, 75 a cutter, a support for sheet material, feed rolls for feeding the sheet material over the support and into cutting position, said feed rolls being spaced from the cutter, and a relatively small feed roll interposed between the first mentioned feed rolls and the cutter and operatively connected to the feed rolls to move synchronously therewith for feeding the end portion of the sheet material into cutting position.
13. In a machine of the class described, 80 a cutter and a cutting block relatively reciprocable toward and from each other in cutting operations, a support for sheet material, feed rolls for feeding the sheet material in successive steps into cutting position, a relatively small feed roll interposed between said feed rolls and the cutter for feeding the end portion of the material into cutting position after it has left the large feed rolls, means for supporting the small feed roll in such manner that it engages the top surface of the sheet material and also an end surface of the portion of material between the large feed roll and the cutter to feed the same into cutting position.
14. In a machine of the class described, 85 a cutter and a cutting block relatively reciprocable toward and from each other in cutting operations, a support for sheet material, feed rolls for feeding the sheet material in successive steps into cutting position, a relatively small feed roll interposed between said feed rolls and the cutter for feeding the end portion of the material after it has left the large feed rolls, a supporting bar in the lower end of which the small feed roll is pivoted, means for yieldingly pressing the supporting bar and feed roll toward the work support, and means for operatively connecting the small feed roll with the larger feed rolls so as to be positively driven thereby.
15. In a machine of the class described, 90 a cutter and a cutting block relatively reciprocable toward and from each other in cutting operations, a support for sheet material, feed rolls for feeding the sheet material in successive steps into cutting position, a relatively small feed roll interposed between said feed rolls and the cutter for feeding the end portion of the material after it has left the large feed rolls, a supporting bar in the lower end of which the small feed roll is pivoted, means for yieldingly pressing the supporting bar and feed roll toward the work support, and means for operatively connecting the small feed roll with the larger feed rolls so as to be positively driven thereby.

terial, feed rolls for feeding the sheet material in successive steps into cutting position, a relatively small feed roll interposed between said feed rolls and the cutter for feeding the end portion of the material after it has left the large feed rolls, a supporting bar having the small feed roll mounted on its lower end, means for yieldingly pressing the bar and feed wheel toward the work support so that the feed wheel engages both the top surface and an end surface of the end portion of the sheet material, and a gear interposed between the first-mentioned feed rolls and the small feed roll for positively driving the latter.

16. In a machine of the class described, cutting means, means for feeding sheet material to the cutting means, the construction and arrangement being such that the feeding means is spaced from the cutting means, and means for feeding the end portion of the sheet material after it leaves the first mentioned feeding means constructed to engage widely spaced portions of the upper surface of said end portion to control positively the movement of said end portion to cutting position, and means for driving both feeding means at the same rate of speed.

17. In a machine of the class described, cutting means, means spaced from the cutting means for feeding sheet material thereto, and a feed roll interposed between the cutting means and the first mentioned feeding means for feeding the end portion of the material a predetermined amount toward the cutting means.

18. In a machine of the class described, cutting means, means spaced from the cutting means for feeding sheet material thereto, and positively operated means constructed to engage the upper surface and subsequently an end surface of an end portion of sheet material to control the end portion of the material after it leaves the first mentioned feeding means for feeding the same a predetermined amount into proper position with respect to the cutting means.

19. In a machine of the class described, work operating means, a table for supporting sheet material, means for feeding the sheet material toward the work operating means, and a presser foot for holding the sheet material upon the table at a point closely adjacent the work operating means during operation of the latter on the work,

said presser foot comprising a positively driven roll operative to direct the end portion of the sheet material into the field of operation of the work operating means.

20. In a machine of the class described, a cutter, a support for sheet material, feed rolls spaced from the cutter for feeding the sheet material thereto, a relatively small feed roll interposed between the first mentioned feed rolls and the cutter for engaging the advance end portion of the sheet material for directing the same into proper position with respect to the cutter, and means for mounting the small roll to maintain it against movement laterally away from the cutter.

21. In a machine of the class described, a tool, a support for sheet material, a feed roll spaced from the tool to feed the sheet material thereto, and a relatively small feed roll interposed between the first-mentioned feed roll and the tool and driven at the same rate of speed and arranged to feed the end portion of the material located between the first-mentioned feed roll and the tool into operative position.

22. In a machine of the character described, a tool, a support for sheet material, and feed rolls comprising large and small rolls operating simultaneously and at the same rate of speed for feeding sheet material to the tool, the construction and arrangement being such that the small feed roll insures the proper feeding of the end portion of the sheet of material into position for the operation of said tool.

23. In a machine of the character described, a tool, a support for sheet material, and feed rolls comprising large and small rolls for feeding sheet material to the tool, the construction and arrangement being such that both large and small feed rolls co-operate in the feeding of all portions of each sheet, the small roll operating to insure the proper feeding of the end portion of the sheet into position for the operation of said tool.

24. In a machine of the character described, a cutter, a support for sheet material, and a set of large and small feed rolls located closely adjacent to the cutter for feeding the sheet material over the support and into operative relation to said cutter.

In testimony whereof I have signed my name to this specification.

WILLIAM C. BAXTER.
